UNITED STATES PATENT OFFICE.

LOUIS A. AUMANN, OF CHICOPEE, MASSACHUSETTS, ASSIGNOR, BY MESNE ASSIGNMENTS, TO DRAPER CORPORATION, OF HOPEDALE, MASSACHUSETTS, A CORPORATION OF MAINE.

WARPING-MACHINE.

1,218,235.

Specification of Letters Patent.

Patented Mar. 6, 1917.

Application filed May 13, 1915. Serial No. 27,931.

To all whom it may concern:

Be it known that I, LOUIS A. AUMANN, a citizen of the United States, residing at Chicopee, county of Hampden, and State 5 of Massachusetts, have invented an Improvement in Warping-Machines, of which the following description, in connection with the accompanying drawings, is a specification, like letters on the drawings representing like parts.

The invention hereinafter described relates to warping machines for winding upon a beam or drum a series of warp threads to be subsequently treated and used in the loom 15 for weaving.

For economic and satisfactory results it is desirable that there shall be wound upon the beam a predetermined length of yarn or warp, and to this end warping machines 20 have heretofore been provided with measuring devices, which, upon registering a predetermined length of yarn wound on the beam, have caused stopping mechanism to be operated to stop the machine. Such 25 measuring devices have been operated from a small roll at the top portion of the machine over which the warp threads pass, but under these conditions some slip is liable to occur resulting in inaccuracy of measurement. Other measuring devices have been 30 operated from the warp beam driving roll, but as the beam load gradually increases during the winding operation of the warp threads thereon, there is found to be a relative slip between the driving surface of the driving roll and the surface of the threads wound on the beam. This slip is liable to occur at any time especially as the beam and its load gradually increase in weight, 35 due to the consequently greater frictional driving power required between the surface of the driving roll and thread load to turn the beam, but is particularly noticeable when stopping to piece broken ends, and 40 starting up again, so that there will be a discrepancy between the length of warp indicated by the measuring device and that actually wound upon the beam at the conclusion of the warping operation.

With these generally-stated facts in mind, the aims and purposes of the present invention are to provide means whereby the measured length of warp on the warp beam as denoted by the measuring device shall be 55 the same as that actually wound upon the

beam. An important feature of the present invention consists in providing the cylindrical driving surface of the warp beam driving roll with a series of projecting portions adapted to engage and sink into the 60 yielding surface of the thread mass wound on the beam, so that a substantially positive driving engagement exists between the surfaces of the driving roll and the wound mass of thread on the beam, and operating 65 the measuring device through connections with the driving roll, the result being that at the end of the warping operation the actual length of warp wound upon the beam 70 will be the same as that indicated by the measuring device.

In the drawings:

Figure 1 is a side elevation of one type of warping machine having the present invention associated therewith;

Fig. 2 is an enlarged sectional detail showing the driving surface of the warp beam driving roll and its action upon the surface of the warp wound upon the beam;

Fig. 3 is a front elevation of the driving roll showing the character of the driving surface.

The machine frame may be of any usual or desired construction, and as shown comprises the side frames 1 rising from suitable base supports 2 and connected by appropriate cross-ties, as will be readily understood.

Mounted on the side frame 1 is a rock shaft 3 from which rises the rocker arm 4 to which is pivotally connected at 5 the pawl 6 adapted to engage and rotate step-by-step a ratchet wheel 7 having an attached worm 8 which engages a worm wheel 9 on the shaft 10. At its upper portion the shaft 10 carries a worm 11 in mesh with a worm wheel 12 which operates the "warper clock" or measuring device comprising a scroll or worm 13 provided with a slot 14. The parts so far described, as well as the finger 15, weight 16, the arm 17 notched at 18 to engage the roll 19 on the vibrator 20, the latch 21 mounted on the rocker arm 4 and having the laterally extending toe 22 adapted to enter between the shipper rod 23 and the knock-off lever 24, when the measuring device indicates that the predetermined length of warp has been wound upon the beam and the machine is to be stopped automatically, may all be substan-

tially the same as shown and described in the patents to Rhoades, No. 624,541, May 9, 1899, or No. 756,800, April 5, 1904, or they may be of any desired construction, the 5 essentials in these respects being that the measuring device shall measure the length of warp wound upon the warp beam and when the desired predetermined length has been wound shall cause the machine to be stopped.

10 Mounted in suitable bearings 25 on the machine frame is the shaft 26 to which is secured in appropriate manner the warp beam driving roll 27. Secured to the rock-shaft 15 3 is a yoke 28 which embraces the cam 29 secured to the driving roll shaft 26, the construction being such that as the driving roll is rotated, as usual from any convenient source of power well understood by those 20 skilled in the art, the shaft 3 will be rocked and through the means described the "warper clock" or warp measuring means will be operated from the warp driving roll; and when the warp measuring means indicates that desired predetermined length of 25 warp has been wound upon the beam, the machine will be stopped.

The warp beam may be of any desired construction, but in the present instance, is 30 shown as formed of a barrel or drum 30 provided with the heads 31. The journals 32 of the warp beam are carried by the arms 33 pivotally connected to the machine frame, as usual, suitable weights 34 being connected to the arms to cause the thread mass 35 wound upon the beam to be held in contact with the driving surface of the driving roll 27.

From the construction described, it will 40 be noted that the warp measuring means is positively driven from the warp beam driving roll; and if the surface speeds of the warp beam driving roll and the wound mass of yarn or thread upon the beam remains 45 the same throughout the winding operation, in other words, if there is no slip between the driving surface of the warp beam driving roll and the surface of the warp wound upon the beam, the measuring device will, 50 at the completion of the warping operation, accurately indicate the length of warp wound upon the beam.

To insure such uniform surface speed of the warp beam driving roll and warp wound 55 upon the beam, the present invention aims to utilize the relative yielding character of the thread mass upon the beam to prevent any relative slip between the surface of the warp beam driving roll and the thread mass 60 upon the beam by providing the cylindrical driving surface of the roll with projecting portions to engage the relatively yielding surface of the thread mass upon the beam and sink thereinto without injurious effect 65 upon the warp threads.

As one form of means to this end, the exterior driving surface of the warp beam driving roll is provided with grooved portions extending longitudinally of the warp beam driving roll and producing between 70 such grooved portions, ribs or projections, the construction being such that the relatively yielding thread mass upon the warp beam will, under the weight of the warp beam and its load, sink into the grooved portions of the driving roll and produce, in effect, a positive driving connection between the surface of the driving roll and the wound mass of warp threads, with the result that as the measuring means is positively driven 80 from the warp beam driving roll and the warp beam is driven without slip from the same driving roll, the length of warp indicated by the measuring means as wound upon the warp beam at the end of a warping operation, will be the same as the actual length 85 of warp wound thereon.

In Fig. 2 of the drawings, the grooved portions in the driving surface of the warp beam driving roll are indicated at 36 and 90 the projecting portions 37 which sink into the thread mass upon the warp beam extend longitudinally of the warp beam driving roll between the grooves 36. In order that the warp threads may not be injuriously affected 95 by the longitudinal projecting portions 37 on the driving surface of the warp beam driving roll, the edges of said projecting portions are rounded, as indicated at 38, Fig. 2.

During the first part of the warping operation, the weight of the warp beam and its load will, of course, be relatively light, and the density of the thread mass during the first layers of windings will be relatively 105 dense, so that at such time the projecting portions or ribs 37 on the surface of the warp beam driving roll will indent themselves less into the thread mass than they will when the thread mass has become relatively large upon the beam; but during the first part of the warping operation, owing to the relatively light weight of the warp beam and its load, the indentations into the thread mass made by the projections or ribs 110 37 will be sufficient to insure a positive drive between the warp beam driving roll and thread mass, and as the warp load increases upon the beam and in consequence the beam and its load becomes heavier, the yielding 115 character of the thread mass increases so that a more pronounced indentation of the projecting portions or ribs 37 will take place in proportion to the increased driving power necessary to turn the now heavier beam and its load.

While the invention has been shown and described in the present instance as associated with a warping machine of the type disclosed in the Rhoades patents hereinbe- 120

fore mentioned, it will be manifest that it is not restricted thereto, but may be appropriately employed in any warping machine wherein there is a warp beam driving roll 5 upon which the thread mass on the warp beam rests and by which it is driven, and wherein, also, there is a measuring device driven from the warp beam driving roll, so that at the end of a warping operation, the 10 length of warp actually wound upon the beam will correspond to that indicated by the measuring means.

What is claimed is:—

1. In a warping machine for winding 15 warp yarn upon a beam, the combination of warp measuring means, a warp beam driving and supporting roll for sustaining and rotating the warp beam and its load and having a driving surface formed with portions to engage and sink into the yarn mass 20 on the beam and insure that the beam load shall be driven at the same surface speed as that of the driving roll, and connections between the warp beam driving roll and measuring means for operating the latter from 25 the former to insure that the measured length of yarn on the beam as indicated by

the warp measuring means shall be the same as the actual length wound thereon.

2. In a warping machine for winding 30 warp yarn upon a beam, the combination of warp measuring means, a warp beam driving and supporting roll for engaging the warp wound upon the warp beam and supporting the weight of the warp beam and 35 its yarn load, said warp beam driving roll having a driving surface provided with rounded projecting portions to non-injurious 40 engage and sink into the yarn on the warp beam and prevent slip between the driving roll and warp beam load, connections between the warp beam driving and supporting roll and the warp measuring means for operating the latter from the former, and stopping means for stopping the 45 machine when the predetermined length of yarn has been wound upon the beam.

In testimony whereof, I have signed my name to this specification, in the presence of two subscribing witnesses.

LOUIS A. AUMANN.
